UNITED STATES PATENT OFFICE.

ADDISON F. KELLEY, OF FREELAND PARK, INDIANA.

DUSTPAN.

1,315,310.

Specification of Letters Patent. Patented Sept. 9, 1919.

Application filed April 18, 1917. Serial No. 162,963.

To all whom it may concern:

Be it known that I, ADDISON F. KELLEY, a citizen of the United States, residing at FreeLand Park, in the county of Benton, 5 State of Indiana, have invented certain new and useful Improvements in Dustpans; and I do hereby declare the following to be a full, clear, and exact description of the invention, such as will enable others skilled 10 in the art to which it appertains to make and use the same.

This invention relates to the class of dust pans in which there is provision for combining the brush used in connection with the 15 pan and the object of the invention is to provide a structure that will have the durability necessary to withstand the adverse use to which it is put and which nevertheless will be economical of manufacture.

20 Figure 1 is a plan view of the dust pan constructed in accordance with the invention.

Fig. 2 is a side elevation thereof.

Fig. 3 is a front elevation thereof.

25 Fig. 4 is a longitudinal section.

Referring more particularly to the accompanying drawing in which like reference characters indicate similar parts the 30 numeral 5 indicates the base of the dust pan which is made of any preferred material and provided with the sides 6, back 7 and cover 8. A handle 9 is extended from the back 7 intermediate its ends.

The forward transverse edge of the cover 35 8 is preferably bent upon itself to provide the angular flanges 10 and 11, the former of which is provided with a plurality of openings 12 therein arranged contiguous to the edge formed by the intersection of said flanges. A tooth 13 is mounted in each of the openings 12 and an intermediate portion of said tooth is engaged with the inner 40 surface of the flange 11 and may be secured thereto by soldering. The solder may

be run into the channel formed between the 45 cover member 8 and the flanges 10 and 11, after the pins have been engaged in the perforations 12 and before the cover member has been horizontally positioned. The 50 rear ends of the teeth 13 are projected beyond the inner edge of the flange 11 and the front ends of the teeth are extended, in parallel relation, a considerable distance beyond the forward edge of the cover 8 and are sharpened as indicated at 14. It will 55 be apparent from this description that a broom or brush may readily be cleaned and particles of hair and the like removed therefrom by inserting the teeth into the body of the brush and then pulling thereon until 60 the teeth are free of the outer ends of the bristles of the brush or broom, at which time the dirt removed will fall into the dust pan.

What is claimed is:—

65 A dust pan comprising a base, sides, back and a top extending from the back partway over the base, the forward edge portion of the top being bent rearwardly between itself and the base and in spaced relation to itself with a resultant vertical flange and a resultant horizontal flange, the vertical flange having a transverse series of spaced perforations therethrough, a series of parallel spaced pins engaged each in a perforation 70 and extending between said horizontal flange and the top member and extending also forwardly beyond the vertical flange, and a body of retaining solder filled into the space between the top member and the 75 vertical and horizontal flanges and binding the pins thereto.

80 In testimony whereof I affix my signature in the presence of two witnesses.

ADDISON F. KELLEY.
